UNITED STATES PATENT OFFICE.

JOHN OLSON, OF DELAVAN, ILLINOIS.

DESIGN FOR A TIRE.

● 57,856.

Application filed November 6, 1920. Serial No. 422,399. Term of patent 14 years.

To all whom it may concern:

Be it known that I, JOHN OLSON, a citizen of the United States, residing at Delavan, in the county of Tazewell and State of Illinois, have invented a new, original, and ornamental Design for Tires, of which the following is a specification, reference being had to the accompanying drawing, forming part thereof.

Specification for Design.

Patented May 10, 1921.

Figure 1 is a plan view of a portion of a tire showing my new design.

Fig. 2 is a cross section on line 2—2 of Fig. 1.

I claim:—

The ornamental design for a tire, as shown.

JOHN OLSON.
